COMBINED CUP AND SAUCER SERVING UNIT

Gerald Gulotta, New York, N.Y., assignor to Block China Company, a partnership of Elizabeth Block, Jay L. Block, and Robert C. Block, all of New York, N.Y.

Filed Dec. 16, 1964, Ser. No. 83,057

Term of patent 14 years

(Cl. D44—9)

FIG. 1

FIG. 2

FIG. 3

FIG. 4

FIG. 5

FIGURE 1 is a top view of the combined cup and saucer serving unit showing the novel design;

FIGURE 2 is a front view thereof;

FIGURE 3 is a bottom view thereof;

FIGURE 4 is a rear view thereof;

FIGURE 5 is an enlarged scale, cross-sectional view on line 5—5 of FIG. 1.

The essential features of the design are shown in full lines and reside primarily in the continuous convex curve defined by the interrelationship between the side surface of the cup and the upper surface of the saucer.

I claim:

The ornamental design for a combined cup and saucer serving unit, substantially as shown and described.
